UNITED STATES PATENT OFFICE.

SHERMAN BARBER, OF OAK PARK, ILLINOIS.

NUT-LOCK.

1,324,023.

Specification of Letters Patent.

Patented Dec. 9, 1919.

Application filed December 5, 1918. Serial No. 265,321.

To all whom it may concern:

Be it known that I, SHERMAN BARBER, a citizen of the United States, residing in the city of Oak Park, county of Cook, and State of Illinois, have invented certain new and useful Improvements in Nut-Locks, of which the following is a specification.

This invention relates to improvements in nut locks and has among its salient objects to provide a construction in which the nut lock has in effect a double locking action on the nut; to provide a construction in which this double locking action is preferably obtained by spring locking action; to provide a construction in which a double locking action can be obtained from a single piece of metal, shaped and bent to the desired form; to provide a construction in which one element of the locking members has in effect a coil spring or helical spring action and the other a leaf spring action; to provide a construction which can be formed from a single piece of flat metal shaped and bent in accordance with the invention; to provide a construction which while securely locking the nut against working loose from the bolt, nevertheless does not interfere with the wrench action in removing the nut or turning it into place; to provide a construction which can be readily and economically manufactured and in general to provide an improved construction of the character referred to.

In the drawings,

Figure 1 is a cross sectional view of a rail joint;

Fig. 2 is a side elevation with parts broken away;

Fig. 3 is a perspective view of the nut lock itself;

Fig. 4 is a view taken on lines 4—4 of Fig. 3 and looking in the direction of the arrows.

In the particular construction shown in the drawings I have shown the invention as used in connection with fastening rails by means of the fish plates, although it is to be understood that the invention is not limited to any such use, but may be applied to wherever it is desired to lock a nut to a bolt or threaded rod except, it is to be understood that the nut lock must have a suitable support for the leaf spring action to rest on.

Referring to the drawings—1 designates a railway rail, 2 and 3 the fish plates. The fish plates are secured to the rails by means of bolt 4, which is provided with the usual nut 5. Between the fish plate 3 and the inner face of the nut 5 is interposed my improved nut lock designated as a whole 6. This nut lock 6 consists primarily of an annular split ring portion 7, a leaf spring member 8 and a connecting portion 9. The split ring portion 7 has its free end offset as shown at 10 which off set portion acts to bite against or have locking frictional engagement with the adjacent face of the nut. The leaf spring portion 8 has a central convex portion 11 and ends 12 and 13. The end 12 is connected to the intermediate portion 6 heretofore referred to. As shown in the drawings, the device is made from a single piece of flat metal and the split ring portion is bent so that the split ring portion lies vertical while the leaf spring portion has the metal lying substantially horizontal or flat.

The nut lock is operated as follows: After the bolt is inserted in place, the split ring portion 7 is inserted over the threaded end of the bolt so that the leaf spring rests on the horizontally inclined portion of the fish plate as shown clearly in Fig. 1. This portion of the fish plate, last referred to, merely serves as a support for the leaf spring. The nut is now threaded on the bolt. As the nut is turned it will force the convex portion of the leaf spring downwardly sufficiently to permit of the nut being turned by the wrench, but will at the same time prevent this convex portion of the leaf spring working loose. As the nut engages the split ring portion, it will force the off set portion 10 back, the arrangement being such that this off set portion 10 has a spring gripping action against the face of the nut without however preventing the nut from being tightened by means of the wrench.

I am aware that numerous inventions on nut locks have heretofore been patented, but as far as I am aware none of them combines the advantages, both in simplicity of construction and reliability of operation of the present device.

I claim as my invention:

1. A nut lock consisting of an annular

split ring portion having an offset extension and shaped to afford helical spring action, a convex leaf spring portion extending substantially at right angles to the ring portion, 5 a portion connecting the leaf spring and split ring portions.

2. A nut lock consisting of an annular

split ring portion having an offset extension and shaped to afford helical spring action, a leaf spring portion at an angle to the ring 10 portion, a portion connecting the leaf spring and split ring portions, and all of said portions being formed of a single piece of metal.

SHERMAN BARBER.
